(56) **References Cited**

FIG. 1 is a perspective view of an interior skylight screen,
showing a first embodiment of my new design;

FIG. 2 is a bottom plan view of FIG. 1;

FIG. 3 is a top plan view of FIG. 1;

FIG. 4 is a left-side elevational view thereof, the right-side
elevational view being a mirror image thereof;

FIG. 5 is a front elevational view thereof, the rear elevational
view being a mirror image thereof;

FIG. 6 is a perspective view of a second embodiment thereof;

FIG. 7 is a bottom plan view of FIG. 6; and,

FIG. 8 is a top plan view of FIG. 6.

The broken lines showing an internal skylight in FIGS. 1 and
6 depict environmental matter and form no part of the claimed
design. It is understood that FIGS. 4 and 5 represent both
embodiments.
